[57] **CLAIM**

The ornamental design for a combined headband and nosepiece or similar article, substantially as shown and described.

DESCRIPTION

FIG. 1 is a perspective view of a combined headband and nosepiece or similar article showing my new design;

FIG. 2 is an enlarged front elevational view in folded condition;

FIG. 3 is a rear elevational view thereof;

FIG. 4 is a top plan view thereof;

FIG. 5 is a side elevational view, the opposite side being a mirror image thereof; and

FIG. 6 is a bottom plan view thereof.

FIG. 1

FIG. 2

FIG. 3

FIG. 4

FIG. 5

FIG. 6
